[57] CLAIM

The ornamental design for an external lead adaptor for wrist-worn cardiac monitor, as shown and described.

DESCRIPTION

FIG. 1 is an isometric view of an external lead adaptor for wrist-worn cardiac monitor showing our new design;

FIG. 2 is a top plan view thereof shown on a slightly larger scale than FIG. 1;

FIG. 3 is a right side elevation thereof, shown on approximately the same scale as in FIG. 2, the left side elevation thereof being a mirror image, with the heart watch and a flexible electrical conductor shown in broken lines for illustrative purposes only and forming no part of the claimed design;

FIG. 4 is a front elevation thereof, shown on approximately the same scale as in FIG. 2;

FIG. 5 is a rear elevation thereof, shown on approximately the same scale as in FIG. 2;

FIG. 6 is a bottom plan view thereof, shown on approximately the same scale as in FIG. 2; and,

FIG. 7 is a perspective view thereof, with the viewpoint on the opposite side of the adaptor and at a lower elevation than shown in FIG. 1, and the adaptor shown on approximately the same scale as in FIG. 1.
